PRIMING APPARATUS FOR CENTRIFUGAL PUMPS

Augustus C. Durdin, Jr., Niles Center, Ill., assignor to Chicago Pump Company, Chicago, Ill., a corporation of Illinois

Application February 11, 1935, Serial No. 6,003

13 Claims. (Cl. 103—113)

This invention relates to priming apparatus for centrifugal pumps, and its principal object is to provide novel means for preventing water or other liquid from entering the priming pump. Another object is to provide novel means for priming two or more centrifugal pumps by a single priming pump. Another object provides novel priming means in connection with duplex centrifugal pumps or a battery of centrifugal pumps, whereby the priming of any pump, while another is or others are in operation will not interfere with the operation of any of the pumps.

Another object is to provide a pumping system in which a "wet" vacuum or "dry" vacuum pump may be employed for priming one or several centrifugal pumps. Another object is to provide novel means whereby the priming pump may remain idle except when necessary to prime any one of the centrifugal pumps served by it.

Other objects and advantages will appear in the course of this specification and with all of said objects and advantages in view, this invention consists in the several novel features herein-after fully set forth and claimed.

The invention is clearly illustrated in the drawings accompanying this specification in which:

Fig. 1 is a diagrammatic view, in side elevation, of a centrifugal pump unit equipped with one form of the priming apparatus embodying the present invention;

Fig. 2 is a detail vertical section through the primer seen in Fig. 1;

Fig. 3 is a detail horizontal section taken on the line 3—3 of Fig. 2;

Fig. 4 is a detail horizontal section taken on the line 4—4 of Fig. 2;

Fig. 5 is an end elevation of a duplex pumping installation equipped with a common vacuum tank or chamber connected to the primer of each pump;

Fig. 6 is an end elevation of a duplex pumping installation equipped with a single motor driven priming pump controlled by the primer of each centrifugal pump, and

Fig. 7 is a side elevation of a single centrifugal pump unit equipped with a continuously driven priming pump.

Referring to said drawings, and first to Figs. 1 to 4 inclusive, the reference character 10 designates a base having a raised pad 11, upon which is mounted an electric motor 12. Mounted on the base is a centrifugal water pump 14 of conventional form, the shaft of which is connected to the motor shaft by a shaft coupling 15. Pedestals 13 support the pump casing in co-axial alignment with the motor shaft. A suction inlet pipe 16 connects with the suction inlet of the centrifugal pump 14 through a T fitting 18 and a discharge pipe 17 leads from the discharge outlet of the pump. 19 designates a cap or cover for a clean cut opening in the T coupling 18. A check valve is interposed in the discharge pipe as usual.

Bolted or otherwise secured to the top of the fitting 18 is a primer chamber housing 20, which provides a float chamber 21, in which is contained a float 22 mounted on a float rod 23, which is guided for vertical movement in a bushing 24. Above the float chamber 21 is an air chamber 44 in which is contained valves and other mechanism as will be presently described. A dia-

phragm or wall 25 bolted to a flange 27 on the upper end of the housing 20, separates the float chamber from the air chamber. Desirably the housing 42, which encloses the air chamber 44, and the diaphragm 25, are fastened to the housing 20 by bolts 28 and nuts 29, 43. A gasket 26 is desirably interposed between the flange 27 and the housing 42 and diaphragm 25 to make a tight joint therebetween.

An air passage or port extends through the diaphragm 25, which affords communication between the float chamber and air chamber. The port is closed by a check valve 30, which seats upon the seat 32 of a cage 31 that is fastened in the opening in the diaphragm. Cross wires 33 secured to said cage above the valve 30 serve to retain the valve in the cage.

Extending into the air chamber 44 is a suction fitting 37, desirably having a flange 38 on its outer end bolted to the side wall of the housing 42 by bolts 40. A gasket 39 between the side wall and flange makes a tight joint between the housing and suction fitting. A suction pipe 41 leads from the suction fitting 37 to a suction pump or other vacuum device 52.

An air port is formed in the lower wall of the suction fitting 37, which affords a communication between the air chamber 44 and the interior of the suction fitting. In the port is a valve seat 36 upon which may seat an air valve 35, mounted upon the upper end of the float rod 23. The air chamber provides an air passage from the float chamber to the suction fitting 37. It is to be understood that in priming the centrifugal pump, air is exhausted from the float chamber, and suction inlet pipe 16, thereby permitting water to rise and enter the centrifugal pump and float chamber. The air suction passage to the vacuum pump leads from the float chamber, past the check valve 30, through the air chamber 44, the

port in the valve seat 36, the suction fitting 37 and the suction pipe 41. When the centrifugal pump has been primed, the level of the water in the float chamber rises to a certain level therein, 5 the float is lifted and it seats the air valve 35 upon the seat 36 around the port in the suction fitting, thereby permitting the check valve 30 to close. Suction, produced by the vacuum pump, is then cut off from the air chamber and float 10 chamber, but the closing of the check valve 30 prevents air from entering the float chamber from the air chamber.

In the upper wall of the housing 42 is a vent port surrounded by a valve seat 47, and controlling said vent port is a vent valve 46, which is connected to and operated by the float. Desirably the connections between the vent valve and float may comprise a valve stem 45 on which the valve 45 is mounted and a yoke 34 to which the 20 float rod 23 and valve stem 45 are fastened. Inasmuch as the float supports the weight of the float rod, air valve yoke, valve stem and vent valve, and since the float must unseat the vent valve against atmospheric pressure opposing the 25 partial vacuum in the air chamber, the water will rise a considerable distance in the float chamber before the float will be lifted, and when this occurs, the float and parts carried thereby are lifted suddenly, thereby suddenly closing the air 30 port 36 and opening the vent port 47, and breaking the vacuum in the air chamber. In case of any leakage around the valve 35, air only will enter the suction fitting and be carried to the vacuum pump. The parts are so proportioned 35 and arranged that it is impossible for any water to enter the suction fitting and since the air chamber is at atmospheric pressure (when the vent valve is open) and since the pressure in the float chamber is below atmospheric pressure, 40 there is no likelihood for water being carried on to the vacuum pump.

In Fig. 1 the priming pump 52 and its motor 54 are shown as comprising a priming pump unit, separate from the water pumping unit. The 45 priming pump 52 here shown is of the "dry" pump type, driven from the motor 54 by a belt 53, trained around belt pulleys on the motor and pump shafts respectively. A union coupling 51 and a check valve 51^a are desirably interposed in 50 the suction pipe 41.

In connection with the form of the invention illustrated in Fig. 1, it is desirable to stop the priming pump when the centrifugal pump has been primed, and to permit the priming pump to 55 remain idle so long as the centrifugal pump remains primed, and to start the priming pump, when the centrifugal pump again requires priming. Automatic means have been provided for this purpose, and as shown said means comprise 60 a float switch 50 in the wiring circuit 55 to the priming pump motor 54. A bracket 56 supports the switch on the housing 42. Buttons 48, adjustably mounted on the upper end of the valve 65 stem 45 are placed on both sides of the switch lever 49 of the float switch 50, and operate the same. Upward movement of the valve stem serves to open the switch and downward movement serves to close it. Consequently when the 70 float moves upward, when the centrifugal pump has been primed, the lower button raises the switch lever, opens the circuit and stops the motor 54 and priming pump 52. In case air finds its way into the float chamber and the water in the 75 chamber recedes sufficiently to lower the float, the

upper button lowers the switch lever, closes the switch and again starts the priming pump motor.

As a result the priming pump is operated only as needed. When the centrifugal pump is shut down, the main switch (not shown) for the wiring 5 circuit to the priming pump motor is opened by the attendant.

The operation of the priming apparatus, in general, is as follows: The circuits to the motors 12 and 54 are closed by the attendant, thereby 10 setting the pumping outfit into operation. The suction inlet pipe and float chamber being empty, the float is down, the air valve 35 open and the vent valve 46 closed. The priming pump applies suction through the suction pipe and exhausts air 15 from the air chamber 44, the float chamber 24 and the suction inlet pipe 16, permitting the water to rise in the suction inlet pipe, prime the centrifugal pump and enter the float chamber. When the level of the water in the float chamber 20 rises to a predetermined place, the float is suddenly lifted up, and it closes the air valve and opens the vent valve, thereby cutting off the vacuum supply and opening the air chamber to the atmosphere, whereupon the check valve 30 closes 25 and holds the vacuum in the float chamber. Simultaneously the lower button on the valve stem raises the switch lever 49 and opens the switch 50 thereby opening the circuit for the priming pump motor and stopping the priming 30 pump. In case the water in the float chamber recedes far enough to permit the float to drop, the vent valve 46 is closed, the air valve 35 opened, and the switch is closed, thereby starting the priming pump unit, and restoring the level of the 35 water in the float chamber to its former level, with the vent valve open and the air valve closed.

In the modified form of the invention illustrated in Fig. 5 two centrifugal pump installations substantially similar to the one shown in Fig. 1, are illustrated. The corresponding parts of each installation and those of the form shown in Fig. 1 are indicated by similar reference characters. In this case, however, the float switch 50 is omitted from each installation, and the suction pipe 41, from each air chamber housing 42, lead to a vacuum tank or other vacuum chamber 57. Union couplings 51 and shut off valves 58 are shown as interposed in the suction pipes 41. The arrangement shown in Fig. 5 is intended for situations where it is desirable to maintain a substantially constant vacuum supply on the primer of each centrifugal pump while either or both are in operation. A priming pump unit, comprising an electric motor 62 and a vacuum pump 61, driven thereby, is employed. The vacuum pump 61 is connected to the vacuum tank or chamber 57 by pipe connections 63, having a check valve 63^a therein. Desirably the vacuum tank 57 and priming pump unit are mounted 60 on a base 60. Pedestals 59 support the vacuum tank thereon.

For maintaining a substantially constant low pressure in the vacuum tank 57, a pressure switch is connected to the tank and controls the wiring 65 circuit 66 for the priming pump motor 62. As shown the pressure switch comprises a diaphragm 64 connected to the tank and an electric switch 65 operated thereby. A pressure gauge 67 connected to the vacuum tank indicates 70 the pressure therein. The pressure switch is set to open and close the circuit for the priming pump motor when the pressure in the vacuum tank, reaches certain high and low points.

In this form of the invention the priming pump 75

unit continues to build up vacuum in the vacuum tank until the predetermined high vacuum is reached and thereupon the pressure switch operates and opens the circuit to the priming pump motor. When the pressure in the tank rises for any reason to the high point of the pressure range, the vacuum switch operates and closes the circuit and again starts the motor. In this way a substantially constant low pressure, within predetermined limits, is maintained in the vacuum tank. The operation of the primers of the two centrifugal pumps is substantially the same as that of the primer of the preferred form. Obviously as many centrifugal pumping units may be connected to the vacuum tank as are required.

In the modified form of the invention illustrated in Fig. 6, which also illustrates a duplex pumping installation, the two pumping units and the priming pump unit are substantially of the same construction as those illustrated in Figs. 1 to 4 inclusive, except that only one priming pump unit is employed in connection with the two centrifugal pumps. In this arrangement the two suction pipes 41 are connected to the single suction pipe 69 of the priming pump 70 by a T fitting 68. The reference characters 51 designate union couplings in the lines 41, and 58 designate shut off valves therein. A check valve 30 73 desirably is interposed in the pipe 69.

The priming pump is driven by an electric motor 71, belted or otherwise connected thereto, and the wiring circuit 72 for the motor is controlled by the float switches 50, which are in 35 parallel in the circuit 72.

In this arrangement, when either centrifugal pump 14 requires priming, its associated float switch closes the circuit for the priming pump motor and starts the motor and its priming pump, 40 and when both centrifugal pumps are primed the float switch 50 of the last pump to be primed, opens the circuit to the priming pump motor. As a result the priming pump unit operates only when it is necessary to prime either or both centrifugal pumps. Obviously as many pumping units may be handled by the single priming unit as are required.

In the modified installation illustrated in Fig. 7 the centrifugal pump unit is substantially 50 the same as that illustrated in Fig. 1 except that no float switch is used. In this case, however, the priming pump 74 is mounted on the base 10 and is continuously driven by the centrifugal pump motor 12, as by a belt 76 trained around belt 55 pulleys on the motor shaft and pump shaft respectively. The priming pump is shown as resting on a pad 75. The air chamber of the primer is connected to the priming pump by a suction pipe 41 as in Fig. 1 and to prevent an excessive 60 vacuum from being built up, a relief valve 78 is interposed in the suction line, which is arranged to open to the atmosphere whenever the pressure reaches a predetermined low point. Desirably a check valve 77 is interposed in the 65 suction pipe between the primer and the relief valve.

In the operation of this form of the invention, suction is continuously applied to the primer, and up to the suction fitting 37 (see Fig. 2) 70 when the valve 35 is closed, because the priming pump operates continuously, but the relief valve prevents an overload on the priming pump and motor, as it opens when the pressure reaches a predetermined low place.

75 It is to be observed that under no circum-

stances can water be drawn into the priming pump. This permits the use of a "dry" priming pump without any danger of injury thereto. However, I do not wish to limit myself to a "dry" priming pump as any approved form of suction pump may be substituted therefor. 5

Furthermore, an air passage is provided in the primer which is capable of supplying air at atmospheric pressure to the air valve while the vent is open and the air valve is closed without 10 breaking the vacuum in the suction pipe. As a result thereof, in case of a leaky air valve, air at atmospheric pressure will find its way through the leak to the suction pipe, but it is impossible for any water to reach the suction pipe. In case 15 of a leaky check valve, any air flow between the air chamber and float chamber (when the air chamber is vented) would be from the air chamber, through the leaky check valve, to the float chamber, and as a consequence water cannot 20 be drawn into the suction pipe.

It is also to be observed that when the float lifts and closes the inlet port to the suction pipe 41, air cannot enter the suction pipe from the vent at the top of the air chamber or from any 25 other place. As a consequence the vacuum in the suction line is not broken, but is constantly ready to serve any other centrifugal pump handled by the priming pump or other source of vacuum supply. 30

Other modifications are possible without departing from the spirit of this invention. I desire, therefore, not to limit myself to the exact forms of the invention illustrated, but intend in the following claims to point out all of the invention disclosed. 35

I claim as new and desire to secure by Letters Patent:

1. In priming apparatus for centrifugal pumps, the combination of a float chamber communicating with the suction inlet of a centrifugal pump, a float in said chamber, a second chamber communicating with the float chamber through a valve controlled port, said second named chamber having a vent port, a priming pump and a 40 suction conduit leading therefrom to the second named chamber and having a suction inlet, opening therefrom, and valves operated by the float, for simultaneously closing the suction inlet to the suction pipe and opening the vent port, 50 when the float is raised, the valve for the port between the two chambers operating to close when the vent port is opened.

2. In priming apparatus for centrifugal pumps, the combination of a float chamber communicating with the suction inlet of a centrifugal pump, a float in said chamber, a second chamber communicating with the float chamber through a valve controlled port, said second named chamber having a vent port, a continuously running priming pump and a suction conduit leading therefrom to the second named chamber and having a suction inlet, opening therefrom, and valves operated by the float, for simultaneously closing the suction inlet to the 60 suction pipe and opening the vent port, when the float is raised, the valve for the port between the two chambers operating to close when the vent port is opened. 65

3. In priming apparatus for centrifugal pumps, 70 the combination of a float chamber communicating with the suction inlet of a centrifugal pump, a float in said chamber, a second chamber communicating with the float chamber through a valve controlled port, said second named chamber 75

ber having a vent port, a priming pump and a suction conduit leading therefrom to the second named chamber and having a suction inlet, opening therefrom, valves operated by the float, for simultaneously closing the suction inlet to the suction pipe and opening the vent port, when the float is raised, the valve for the port between the two chambers operating to close when the vent port is opened, an electric motor for driving said priming pump, and an electric switch in the wiring circuit to the motor, responsive to fluctuations in the float chamber.

4. In priming apparatus for centrifugal pumps, the combination of a float chamber communicating with the suction inlet of a centrifugal pump, a float in said chamber, a second chamber communicating with the float chamber through a valve controlled port, said second named chamber having a vent port, a priming pump and a suction conduit leading therefrom to the second named chamber and having a suction inlet, opening therefrom, valves operated by the float, for simultaneously closing the suction inlet to the suction pipe and opening the vent port, when the float is raised, the valve for the port between the two chambers operating to close when the vent port is opened, an electric motor for driving said priming pump, and a float switch in the wiring circuit to the motor, responsive to fluctuations in the float chamber.

5. In priming apparatus, the combination of several centrifugal pumps, each having a float chamber communicating with the suction inlet of the pump, a float in the float chamber, a second chamber having an air vent and a vent valve therefor, said second named chamber communicating with the float chamber through a valve controlled port which closes when the air vent is opened, a suction pipe leading from the second named chamber and having a suction inlet opening therefrom, a suction inlet valve, and operative connections between the valves and float whereby the vent valve is opened and the suction inlet valve is closed when the float is raised; and a single source of vacuum supply connected to all of the suction pipes.

6. In priming apparatus, the combination of several centrifugal pumps, each having a float chamber communicating with its suction inlet, a float in said float chamber, a second chamber having an air vent and a vent valve therefor, said second named chamber communicating with the float chamber through a valve controlled port which closes when the air vent is opened, a suction pipe leading from the second named chamber and having a suction inlet opening therefrom, a suction inlet valve, and operative connections between the valves and float whereby the vent opens and the suction inlet closes when the float is raised; a vacuum tank connected to the suction pipes, an electric motor operated vacuum pump connected to the vacuum tank, and a pressure switch connected to the vacuum tank and interposed in the wiring circuit to the motor of the vacuum pump.

7. In priming apparatus, the combination of several centrifugal pumps, each having a float chamber communicating with its suction inlet, a float in said float chamber, a second chamber having an air vent and a vent valve therefor, said second named chamber communicating with the float chamber through a valve controlled port which closes when the air vent is opened, a suction pipe leading from the second named chamber and having a suction inlet opening therefrom, a suction inlet valve, and operative connections

between the valves and the float whereby the vent valve opens and the suction inlet valve closes when the float is raised; an electric motor driven vacuum pump having pipe connections with said suction pipes, and float switches operated by said floats, said float switches being in parallel in the wiring circuit to the motor of the vacuum pump.

8. In priming apparatus for centrifugal pumps, the combination of a float chamber communicating with the suction inlet of a centrifugal pump, a float in said float chamber, a valve chamber communicating with the float chamber through a check valve controlled port, a suction fitting entering said valve chamber and having an inlet port opening to the interior of the valve chamber, a suction pipe leading from said suction fitting and connected to a source of vacuum supply, there being a vent opening to the interior of said valve chamber, and valves connected to and operated by said float for simultaneously closing the inlet to the suction fitting and opening the vent when the float is raised.

9. In priming apparatus for centrifugal pumps, the combination of a float chamber communicating with the suction inlet of a centrifugal pump, a float in said float chamber, a valve chamber communicating with the float chamber through a check valve controlled port, a suction fitting entering said valve chamber and having an inlet port opening to the interior of the valve chamber, a suction pipe leading from said suction fitting and connected to a source of vacuum supply, there being a vent opening to the interior of said valve chamber, valves controlling the inlet to the suction fitting and the vent, a float rod connecting the float with one of said valves, a valve stem connected to the other valve, and a yoke extending around the suction fitting and connecting the float rod with the valve stem.

10. In priming apparatus for centrifugal pumps, the combination of a float chamber communicating with the suction inlet of a centrifugal pump, a float in said float chamber, a second chamber located above the float chamber and having an air vent and a valve therefor which is opened when the float rises, and there being a port between said chambers closed by a check valve, a suction fitting spaced above the bottom of the second named chamber and having a suction inlet port opening to said second named chamber, a suction pipe leading from said suction fitting to a source of vacuum supply, and a valve operated by the float for closing the suction inlet port to the suction fitting when the float is lifted.

11. In priming apparatus for centrifugal pumps, the combination of a float chamber communicating with the suction side of a centrifugal pump, a suction pipe having a suction inlet, a suction inlet valve for the suction inlet, an air chamber having a valve controlled outlet port adjacent the suction inlet, opening to the float chamber, said air chamber having also an air vent and a valve therefor, said vent valve being opened when the suction inlet and the valve controlled outlet port are closed, and said suction inlet, when open, communicating with said air chamber and communicating with said float chamber through said valve controlled outlet port, a float in said float chamber, and operative connections between the vent and suction inlet valves and the float, whereby, when the float is raised, the air vent valve opens and the suction inlet valve closes and

air at atmospheric pressure is thereby admitted to the suction valve without breaking the vacuum in the suction pipe.

12. In priming apparatus for centrifugal pumps, the combination of a float chamber communicating with the suction side of a centrifugal pump, a suction pipe having a suction inlet, a suction inlet valve for controlling said suction inlet, a float in said float chamber connected to and operating to open and close said suction inlet valve, and an air chamber from which the suction inlet to the suction pipe opens, said air chamber opening to the float chamber through a check valve controlled port and having a vent and a vent valve therefor operated by said float, the connections between the valves and float being constructed and arranged to simultaneously open one valve and close the other, said air chamber being adapted to supply air at atmospheric pressure to said suction inlet valve when the

vent is open whereby air only may leak past a leaky valve to the closed pipe.

13. In priming apparatus for centrifugal pumps, the combination of a float chamber communicating with the suction side of a centrifugal pump, an air chamber having a vent and a valve therefor, and having a check valve controlled port opening to the float chamber, a suction pipe having a suction inlet arranged for communication with the air chamber, an air valve for controlling the passage from the air chamber to the suction inlet, and a float in said float chamber connected to the vent valve and air valve, and operating, when lowered to open the air valve and close the vent valve, whereby when the air valve is opened, communication is established between the suction pipe, the air chamber and float chamber, and when closed, communication is closed between the air chamber and suction pipe.

AUGUSTUS C. DURDIN, JR. 20
